GLIDER TYPE FLYING TOY

Jerome E. Johnson, Los Angeles, Calif.

Application April 9, 1956, Serial No. 40,965

Term of patent 14 years

(Cl. D34—15)

Fig. 1

Fig. 2

Fig. 3

Fig. 1 is a plan view of a glider type flying toy showing my new design;

Fig. 2 is a side view of the same; and

Fig. 3 is a sectional view thereof taken on the line 3—3 of Fig. 1.

Portions of Fig. 1 are lined to indicate color contrast.

I claim:

The ornamental design for a glider type flying toy, as shown and described.
